United States Patent Office

Des. 213,047

Patented Dec. 31, 1968

213,047

CLEANING NOZZLE

Virgil Kenneth Steidley, Mansfield, Ohio, assignor to The F. E. Myers & Bro. Co., Ashland, Ohio, a corporation of Ohio

Filed June 5, 1967, Ser. No. 7,365

Term of patent 14 years

(Cl. D23—34)

FIG. 1

FIG. 2

FIG. 3

FIG. 4

FIG. 1 is a perspective view of a cleaning nozzle for fluid under pressure embodying my new design.

FIG. 2 is a sectional view thereof, taken substantially as indicated on line 2—2 of FIG. 4.

FIG. 3 is a view of one end thereof, and

FIG. 4 is a view of the opposite end thereof.

I claim:

The ornamental design for a cleaning nozzle, as shown.
